UNITED STATES PATENT OFFICE.

ERNEST P. CLARK, OF NEW YORK, N. Y., ASSIGNOR TO THE CLARK ELECTRIC COMPANY, OF SAME PLACE.

SAFETY DEVICE FOR DYNAMOS.

(SPECIFICATION forming part of Letters Patent No. 426,109, dated April 22, 1890.

Application filed December 30, 1889. Serial No. 335,299. (No model.)

To all whom it may concern:

Be it known that I, ERNEST P. CLARK, a citizen of the United States, residing in New York city, in the county of New York and

5 State of New York, have invented certain new and useful Improvements in Safety Devices for Series-Wound Dynamos, of which the following is a specification.

In operating series-wound dynamos, if the 10 line-wire is broken by accident or design, the flow of current being interrupted, the electro-motive force falls to a greater or less degree, depending upon the power of the dynamo and the residual magnetism of its field-magnet 15 cores. The electro-motive force which still exists may be sufficient in the case of large powerful dynamos to administer dangerous shocks to persons or animals that may accidentally come in contact with the broken 20 wires. Should the broken wires, in falling, make contact with any other good conductor—such as another wire, an awning-frame, or metallic roof—this conductor becomes part of the circuit, which being thus completed the 25 dynamo at once resumes its action, rendering the accidental portion of the circuit highly dangerous to persons coming in contact with it, as well as being liable to cause fires by reason of the faulty nature of the contacts 30 with the broken ends of wire. Another danger from such an accident is to the dynamo itself. At the moment of interruption of the current the lamps or other translating devices at once assume their condition of lowest resistance.

35 If, then, the circuit is suddenly closed, the dynamo resumes its action instantly, and the result is an abnormal rush of current, which may injure or destroy the dynamo. This is particularly the case if an automatic regulator is used with the machine, such regulators operating to maintain a constant current through a variable resistance when, as in case of a broken line, the resistance becomes very great or infinite, the regulator in the effort to 40 maintain the current will at once apply the greatest electro-motive force the machine can produce, thus increasing the dangers from the broken wires.

The object of my invention is to protect the 45 dynamo from such accidents, as well as to render the wires harmless in the event of their

being broken. Its effect is to put the dynamo out of action the instant the line is broken, and to maintain it in this condition until set to work again manually. 55

Its construction and method of operation are as follows:

A represents a series-wound dynamo, whose working-circuit, containing translating devices, is represented by B. In the working-circuit is also placed a magnet b, whose armature is attached to a pivoted latch-lever b', as shown in Fig. 2. When the magnet is de-energized, a spring draws the end of the lever away from its pole. 65

c represents a pivoted switch-arm having a handle for manual operation. A spring c' is attached to it in such a manner that its tendency is to draw it over into contact with a metallic terminal c², the movement of the arm 70 being limited by a stop-pin c¹. The latch-lever b' is adapted to engage with the arm c and hold it under the tension of spring c' out of contact with the terminal c², and the latch is held in this engagement by the magnet b. 75

The circuits which this device controls are as follows: The lever c is connected, as shown, to the wire 1 proceeding from the last end of the field-magnet coils. The terminal c² is connected by wire 2 to the beginning of the field-magnet coils. It is obvious then that when the switch-arm is in contact with terminal c² a shunt of low resistance is established around the field-magnet coils. 80

Fig. 2 is a side view of the electro-magnet b 85 and the latch b', which it controls.

In operation, therefore, when by accident or otherwise the main circuit becomes broken magnet b loses its power, and the latch b' is pulled out of engagement with switch-arm c, 90 thus allowing it to be forced into contact with terminal c² and to close the shunt-circuit around the field-magnet coils of the machine. The machine, therefore, becomes powerless immediately, and no part of the circuit is in 95 a dangerous condition, nor can it be rendered so until the switch-arm c has been restored to its normal running position. This device will be placed at the generating-station, and whenever the operator there notices the change in 100 the position of the switch he knows that a break has occurred and takes steps to repair

it. He is also careful not to put the switch into running condition again until the necessary repairs have been made. When the machine is stopped, the switch is thrown in the same manner as by an accident, and it is therefore necessary to set the switch when the machine is started up again. This operation necessitates sufficient observation of the apparatus to know whether it is in perfect working condition. It is to be observed that the switch-arm *c* might be placed directly in the main circuit with the magnet, in which case the operation of the switch by the magnet would be to effect a second break in the main circuit, which would remain open until again closed by hand. My preferred form, however, is that described herein in detail.

Having thus described my invention, I claim—

A safety device for dynamo-electric machines, consisting of a magnet in the main circuit, a shunt-circuit around the field-coils of the machine, and a circuit-closer in said shunt-circuit controlled by the said magnet, said circuit-closer consisting of a spring-operated switch-arm, a latch for holding the arm in its open position, said latch being operated by the magnet, and a terminal, into contact with which the arm is to be forced by the spring when it is released by the latch. 30

In witness whereof I have hereunto signed my name in the presence of two subscribing witnesses.

ERNEST P. CLARK.
